CLAIM

The ornamental design for outsole for athletic shoe,
substantially as shown and described.

DESCRIPTION

FIG. 1 is a left side elevational view thereof, the outline
of a shoe in broken lines is environmental only and
forms no part of the claimed design;

FIG. 2 is a right side elevational view thereof;

FIG. 3 is a bottom plan view thereof, the top being
substantially plain and unornamented;

FIG. 4 is a front elevational view thereof; and

FIG. 5 is a rear elevational view thereof.

FIG. 1.

FIG. 2.

FIG. 3.

FIG. 4.

FIG. 5.
